[57] CLAIM

The ornamental design for a shell-fish utensil, as shown
and described.

DESCRIPTION

FIG. 1 is a side elevational view of a shell-fish utensil
showing my new design, the side opposite being a mirror
image thereof;

FIG. 2 is a top or bottom plan view thereof;

FIG. 3 is a left end elevational of FIG. 1; and

FIG. 4 is a right end elevational view of FIG. 1.
